RAZOR BLADE HOLDER

Frank Clement Thessing, Toledo, Ohio

Application May 10, 1933, Serial No. 670,333

1 Claim. (Cl. 30—98)

The present invention relates to a razor blade holder, and more specifically a holder especially adapted for holding a blade in position for sharpening the same.

5 One of the objects of the present invention is to provide a razor blade holder in which any type of razor blade may be inserted therein and positively held for stropping purposes.

A still further important attribute of the invention is to provide a razor blade holder in which the blade may be easily inserted and removed therefrom and which positively maintains the blade in a rigid position therein during the stropping process.

15 A further important object of the invention is to provide a razor blade holder which consists of a few number of parts, and consequently is cheap to manufacture and simple to use.

In the accompanying drawing, forming a part 20 of this application and in which corresponding parts are designated by similar reference numerals,

Figure 1 is a front elevational view of the razor blade holder showing the blade in position there- 25 in,

Figure 2 is a vertical sectional view of Figure 1 taken on line 2—2 thereof,

Figure 3 is a rear elevational view partly in section of the device,

30 Figure 4 is a horizontal sectional view of Figure 1 taken on line 4—4 looking in the direction of the arrows,

Figure 5 is a vertical sectional view of Figure 1 taken on line 5—5, and

35 Figure 6 is a perspective view showing the blade holder removed from its socket.

In the drawing wherein for the purpose of illustration is shown a preferred embodiment of the invention, the numeral 5 designates a length of 40 inherently resilient metal somewhat less in width than the width of the blade 6 and being bent transversely upon itself between the ends thereof to define a pair of blade gripping members 8. It is illustrated in Figure 6 that the blade 6 is closely 45 confined between the blade gripping elements 8 with the forward ends of the blade 6 flatly in engagement with the bight portion 10.

The numeral 14 designates a combined handle and blade restraining device of tubular form in 50 cross section and having an opening extending entirely therethrough for the snug reception of the members 8. It is important to observe that the corners of the blade 6 are formed with rectangular notches or recesses defining what might 55 be said to be projections or extensions, the rear

one of which is snugly received within the forward portion of the combined handle and blade retaining device with the result that the forward end of the member 14 is flatly engaged with the transverse wall of the adjacent rectangular notches in the blade 6. In other words, the forward portion of the member 14 has a two-point contact with the wall of each rectangular recess or notch in the blade, so that the blade is held against transverse as well as longitudinal shift- 10 ing in the holding device 5.

The rear portion of the members 8 have frictional contact with the inside wall of the combined tubular handle and blade restraining device, so that such members are prevented from 15 slipping forward and allowing the blade 6 to shift.

Otherwise expressed, the blade 6 is flatly engaged on opposite faces thereof by the opposed surfaces of the flat blade holding elements 8 and such engagement is maintained through the 20 pressing together of the members 8 while within the tubular handle 14. With the members 8 thus frictionally secured within the tubular handle 14, the forward end of the handle 14 is received within the recessed portions at the rear ends of 25 the blade so that the blade is in turn pressed forward into flat engagement with the bight portion 10 and in this manner the blade is held securely in place while being stropped.

The device is easily taken apart for the re- 30 removal of the blade 6 and may be cleaned in a highly convenient and expeditious manner.

The inherent resiliency in the member 5 urges the blade gripping strips 8 away from each other so that such strips are caused to have effective 35 frictional contact with the inside wall of the handle 14 and at the same time, when the device is taken apart, the strips 8 will tend to move away from each other so as to release the blade 6.

Since the tubular member 14 is open at both 40 ends thereof the same is rendered self-draining after being cleaned and this affords little opportunity for the accumulation of rust.

It is to be understood that the form of invention herewith shown and described is to be 45 taken merely as a preferred example of the same and that such minor changes in arrangement and construction of parts may be made as will remain within the spirit of the invention and the scope of what is claimed.

Having thus described the invention what is 50 claimed is:

In a device for detachably holding razor blades, a blade of the type in which the corners of the blade are provided with rectangular re- 55

cesses to define projections, a length of flat spring metal bent transversely between the ends thereof to define a pair of flat blade gripping elements between which a blade is inserted, with the forward end of the blade flatly in engagement with the bight portion defined by the gripping elements, and a handle having an opening

extending entirely therethrough and being of rectangular form in cross section for the snug reception of said blade holding elements, said forward portions of said handle having means for engaging the longitudinal and transverse sides of the adjacent recesses in the blade. 5

FRANK CLEMENT THESSING.
